United States Patent Office.

JOSIAH M. SMITH, OF WARREN, NEW JERSEY.

Letters Patent No. 80,428, dated July 28, 1868; antedated July 18, 1868.

IMPROVEMENT IN MORTISING-CHISELS.

The Schedule referred to in these Letters Patent and making part of the same.

TO ALL WHOM IT MAY CONCERN:

Be it known that I, JOSIAH M. SMITH, of the town of Warren, in the county of Somerset, and State of New Jersey, have invented a certain new and useful Tenoning-Chisel; and I do hereby declare that the following is a clear, full, and exact description of the same, reference being had to the accompanying drawing, and to the letters and marks thereon, which said drawing forms part of this specification, and, by—

Figure 1 thereof, represents a front view of my chisel, and by

Figure 2, a side view of the same.

This chisel is a double one, both of the parts, *a* and *b*, having two lips, *c* and *d*, so that it will cut both sides of the tenon, cutting the sides and shoulders, and can be operated with a mortising-machine, the same as a mortise-chisel.

This chisel may be made for plain work or for moulded work, and can be used to cut coping, or for halving or dove-tailing, the size and length of the one or the other lip being such as will adapt the chisel to the special kind of work. Both lips, as are shown by the drawings, are tapering from base to point, and inclined upward from outward edge to the shoulder or angle, so that the cutting will commence on the outer surface or edge of the wood, and as the chisel will have a "drawing-cut," the wood will not be as liable to split or fracture as if the ends of the lips were straight.

It will be noticed that the shank of this chisel is round, and when fitted into a round socket, and in which it can readily be secured by a binding-screw or other suitable means, may easily be turned, so as to have the cutting-faces reversed or changed in relation to the board or strip being cut, the chisel cutting on the side or on the end of the strip or board.

What I claim as my invention, and desire to secure by Letters Patent, is—

A tenoning-chisel, constructed to operate in the manner as herein set forth.

This specification signed this 29th day of November, 1867.

JOSIAH M. SMITH.
